DESIGN FOR A FLAG

Robert Foster, New York, N. Y., assignor to New York World's Fair 1939, Incorporated, New York, N. Y., a corporation of New York

Application January 21, 1937, Serial No. 67,210

Term of patent 3½ years

To all whom it may concern:

Be it known that I, Robert Foster, a citizen of the United States, residing at 14 Sutton Place South, New York, county and State of New York, have invented a new, original, and ornamental Design for a Flag, of which the following is a specification, reference being had to the accompanying drawing, forming a part thereof, in which the figure is a face view of a flag embodying my new design, said figure being lined to indicate an orange and blue color scheme with portions in white. The opposite side of the flag presents the same appearance.

I claim:

The ornamental design for a flag as shown and described.

ROBERT FOSTER.
